(57) **CLAIM**

The ornamental design for a tire, as shown and described.

DESCRIPTION

FIG. 1 is a perspective view of the tire showing my new design;

FIG. 2 is a partial front view thereof;

FIG. 3 is a right side elevation view thereof; and,

FIG. 4 is a left side elevation view thereof.

The broken lines represent the border to the unclaimed portions of the interior of the tire.

1 Claim, 4 Drawing Sheets

FIG. 1

FIG. 2

FIG. 3

FIG. 4
